ANTIDETONATING DEVICE

Andrew William Orr, Jr., Detroit, Mich., assignor
to George M. Holley and Earl Holley

Application June 14, 1945, Serial No. 599,385

2 Claims. (Cl. 261—18)

1

The general object of this invention is to provide an airplane carburetor with the means for providing a constant mixture ratio when cruising in the lean or in the rich position and to provide a relatively small addition of fuel when going from the cruising rich to wide open and to provide a relatively larger amount of additional fuel when going from cruising lean to maximum power, and, finally, to substitute water for the enrichening fuel when developing maximum power.

The specific object of this invention is to substitute for the fuel enrichening device a device that will regulate the water which replaces the enrichening fuel.

In devices now in use, an enrichening fluid is used to prevent detonation and to prevent overheating the engine, especially the exhaust valves. By substituting such a fluid as water, a definite economy can be gained and also cleaner combustion, and a cooler exhaust can be obtained. Now, it is desirable to add more enrichening fuel when "cruising lean" than when "cruising rich," so that the resulting total is the same. For the same reason, it is desirable to add more water when going wide open with the control set in "cruising lean" than when set in "cruising rich". In either event, the amount of water consumed per minute should increase with the weight of air. Hence, the same means for maintaining fuel/air ratio constant that is responsive to air flow is made available for maintaining the ratio of water to air constant, so that the air flow regulates the water addition.

This application contains common subject matter to that disclosed in application Serial No. 581,644 filed March 8, 1945, by George M. Holley, Jr., covering an Aircraft carburetor, and application Serial No. 586,606 filed April 4, 1945, by Andrew William Orr, Jr., covering an Enrichening device. Somewhat similar subject matter is disclosed in Serial No. 622,133 filed October 13, 1945, by Stanley M. Udale.

Figure 1 shows the preferred form of my invention.

Figure 2 shows the relation between the fuel/air ratio and air flow with and without the addition of water.

In Figure 1, 10 is the air entrance, 11 is the throat of a venturi, 12 is the throttle, which, when moved to the left counter-clockwise, converts the venturi 11 into a variable venturi, 13 is one of a number of openings into the throat of the variable venturi 11—12, thus formed, 14 is a passage connecting the orifices 13 with the chambers

16, 15 is a passage parallel to and below the passage 14 and connecting the orifice 13 with the chamber 17, 8 is a diaphragm above the chamber 16, 19 is a passage connecting the annular chamber 20 with a chamber 21 immediately above the diaphragm 8, springs 22 and 23 support the diaphragm 8, which carries a metering needle 24, which controls the connection between the chamber 16 and a passage 18, which communicates with a chamber 36.

The annular chamber 20 is in communication with the air entrance 10 through a large number of openings, one of which is numbered 26, so that the pressure of the air entrance exists in the chamber 21. This pressure of the air entering the carburetor also exists in a similar chamber 27, in which there is a similar spring 28 and a diaphragm 29 corresponding to the diaphragm 8 and a spring 30 corresponding to the spring 23 and a metering needle 31 corresponding to the needle 24. This needle 31 forms a restricted communication between the chamber 17 below the diaphragm 29 and a passage 32, which communicates through a restriction 33 with the air inlet pressure line 19. The passage 32 communicates with a chamber 34, so that a diaphragm 37 which separates the chamber 34 from the chamber 36 is supported on one side by the pressure in the pipe 32 and on the other side by the suction in the pipe 18. The pressure in the chamber 34 is higher than the pressure in the chamber 36; that is to say, the valve 24 is normally opened to such a degree as to admit a good deal of the suction in pipe 14 to the chamber 36, whereas the valve 31 is normally closed and only opens at comparatively high suctions, so that substantially atmospheric pressure exists in chamber 34 when cruising lean or cruising rich.

A chamber 38, in free communication with the annular chamber 20, contains a group of altitude bellows 39, which, at altitude, expand and cause the valve 40 to move to the left, compressing the spring 41. The valve 40, which is a balanced valve, then admits a restricted amount of atmospheric air to the passage 25, which communicates freely with the passage 18, which, as stated above, is a suction passage, so that when the bellows 39 expand due to a lowering of the atmospheric pressure in the entrance 10, the pressure in the pipes 25 and 18 rises relative to the pressure in the pipe 32, which pressure is not affected by the bellows 39. At altitude, the influence of the air flow on the diaphragm 37 is thus diminished, and the mixture ratio is thus maintained within the desired limits, that is, approximately constant.

The throttle 12 is rotated by the throttle lever 42, which is connected to the link 43, which in its turn is connected to the link 44 and to the lever 45. This lever 45 and its control disc 43 are shown turned clockwise into a position approaching the wide-open throttle position, and, thus, partially open fuel metering orifices 47 and 48, which are available and admit metered fuel to passages 49 and 50. The manually-controlled valve 77 in the automatic lean position, as shown, obstructs the flow through the restriction 47 and passage 50 by closing the outlet port 155, but permits that metered by the opening 48 to flow freely through the passage 49 and to flow into the chamber 153 through the open port 154. This metered fuel, together with the small quantity of fuel which flows through a bypass 51, past a low-speed adjusting needle 52 into passage 49, communicates through the port 154 with the chamber 53 to the right of a diaphragm 54, which is to the right of the fuel entrance chamber 55, which communicates with a fuel entrance 56 through a fuel venturi 57. Hence, the diaphragm 54 is subject to the pressure drop at the orifice 48 or at orifices 47-48 when valve 77 is moved counter-clockwise 45° to open port 155 to the automatic rich position.

The servomotor valve 58 engages through the diaphragm 62 with the pin 59. The pin 59 engages through the diaphragm 37 with the pin 60, which pin 60 engages through the small diaphragm 158 with the pin 61. In order that the flow shall be regulated, servomotor valve 58 controls the flow of metered fuel from an orifice 65, through a passage 64, past valve 58 to a passage 67, which communicates with a chamber 69 below the valve 66. The pressure in the passage 64 and in a chamber 63 connected thereto is equal to the pressure of the metered fuel in the passage 49 less the drop at the restriction 65. This drop is controlled by the valve 58. The pressure thus regulated in chamber 63 acts on a diaphragm 145, and a spring 166 tends to seat the valve 66. When the fuel flow is excessive compared with the air flow, then the fuel pressure acting on the diaphragm 54 pushes the valve 58 over to the right, out of the position shown, overcoming the air pressure difference due to air flow acting on diaphragm 37. The valves 66 and 58 then partly close as diaphragms 54 and 37 move to the right. When the flow through 64 and 67 is restricted or stops, the pressure in the chamber 63 rises until eventually it equals the pressure in the chamber 53, which controls and restricts the flow past the valve 66. The fuel, thus regulated, flows to the outlet chamber 68, in which is located a valve 70, mounted on a diaphragm 74, to the left-hand side of which is a chamber 171, which communicates through the passage 72 with the unmetered fuel in chamber 55.

A spring 73 tends to push the diaphragm 74 to the left and thus opens the valve 70, which allows fuel to flow through the passage 148 to the engine. The mixture control valve 77 is controlled by a lever 78. When the valve 77 moves clockwise, it moves into the idle cut-off position; when the valve 77 moves counter-clockwise, it moves to the automatic rich position (A. R.). As shown, it is in the automatic lean position. When valve 77 is rotated anti-clockwise 45°, fuel is also admitted from the variable restriction 47, so that the fuel flow through both 48 and 47 controls the pressure in chamber 153. This is the automatic rich position (A. R.).

4

Valve 77 is connected through the link 84 to the lever 85, which controls the rotation of the valve 86. In the position shown, in the center of the valve 86 is a passage communicating with the passage 81, and thus with the L-shaped passage 88, which communicates with the passage 89 and also with the passage 90. These passages 89 and 90 communicate through the restriction 91 to the passage 93 and so to the chamber 94, which communicates with the chamber 69, so that any fuel flowing through the passage 93 is added to the fuel flowing past the restrictions 47-48.

The fuel/air ratio must progressively become richer as the fuel and air flows increase. Otherwise, the engines would become overheated. Obviously, at maximum fuel flow and at maximum air flow, fuel economy is of very minor importance, the major importance being given to power and the greatest importance being given to preventing the engine burning up, and, of course, a rich mixture is much cooler than a mixture which gives perfect combustion.

The fuel flowing through 87 flows out of the chamber 95 to the right of the diaphragm 96, which chamber 95 communicates with the fuel entrance 56 through the passage 97. The fuel flow through the restriction 92 and passage 93 escapes past the diaphragm 107. The chamber 98, to the left of diaphragm 96, communicates with the throat of the venturi 57 through the restricted orifice 99. Valve 100 is carried by the diaphragm 96 and is seated by a compression spring 101 in the chamber 98, so that the flow through the venturi 57 must be great enough to compress the spring 101; otherwise, the valve 100 will not open, so that the valve 100 only opens at high air flows and when the fuel flow is correspondingly high.

49 A passage 102 connects with the restricted orifice 99, and in the position shown is inoperative. When the lever 85 is moved counter-clockwise into the automatic rich position (A. R.), an opening 103 in valve 86 allows fuel to 45 flow towards orifice 99 and along the passage 102 from the passage 104. The jet numbered 160, located in the passage 104, which communicates with the chamber 55, is an important restriction in the fuel metering system. Restriction 99 is 50 inserted only to make the jet 160 of small enough size. The flow through the restriction 160, through the passage 103, through the passage 102, increases the pressure in the chamber 98, so that the valve 100 will not open so much in 55 the cruising rich position for the same fuel flow through the venturi 57, nor will it commence to open until the fuel flow is greater. Jet 99 can be omitted if the suction holes in the venturi throat 57 are of the proper size and are held to 60 close limits in production.

The lower right-hand corner of Figure 1 shows the construction for the control of the water that takes the place of the enrichening fuel.

The outlets from the two restrictions 91-92 63 are conveyed through a common passage 93 to the chamber 94. When the diaphragm 107 closes the right-hand outlet of the passage 93, no amount of fuel from the needle 100 is admitted to the chamber 69. The water in the bottom of the tank 174 is admitted through the pipe 161 past the valve 162, controlled by the solenoid 163, which is controlled by the manually-operated pilot's switch 164. When the valve 162 is opened, water flows up through the passage 165 to the engine. Simultaneously, the pressure of the

water is transmitted down through the pipe 105 to the chamber 106 to the right of diaphragm 107, so that the diaphragm 107 responds to the pressure thus transmitted and closes the end of the passage 93 and compresses the spring 108. The water that flows up 105 passes through a slotted opening 181, then through a passage 182 to a slot 183, which communicates with the chamber 178, in which is located the balanced valve 169, which thus permits the water to flow through the passage 170 to the chamber 69. Valve 184, connected to the throttle lever 110 controls the area of the opening 181, so that as the throttle is opened, the area of the slot 181 increases. A corresponding slot 185 is also controlled by the valve 184. The slot 185 is connected through a passage 186 to a corresponding slot 187, which, in the position shown, is wide open.

Valve 188 in the position shown, has completely uncovered the slot 183. A lever 189 is connected by the rod 190 with the lever 78; the position of this lever 78, which is shown in the automatic lean position, determines whether the controls are in automatic rich, automatic lean or the idle cut-off position. The diaphragm 171, which controls the movement of the balanced valve 169, is responsive to the pressure in the chamber 172. The pressure in the chamber 172 is determined by the pressure in the passage 173, which is connected to the chamber 53, which is the pressure of the fuel on the downstream side of opening 48.

The supply of water under pressure is obtained indirectly from the fuel pump 175, which discharges fuel up the passage 176, which communicates to the upper part of the water tank 174 and thus pushes the water out of the bottom of the water tank 174 into the passage 161. The pressure relief valve 177 prevents the fuel pressure becoming excessive. The pipe 176 communicates with the fuel entrance 56.

Operation

The switch 164 being closed, the valve 162 is opened by the solenoid 163. Then, as the throttle is opened, slots 181 and 185 are opened so that more and more water is admitted to the chamber 178. In the position shown, which is the automatic lean (A. L.), both slots 183-187 are wide open, so that the maximum amount of water is flowing. When the lever 78 moves anti-clockwise to the automatic rich position (A. R.), the valve 188 also moves anti-clockwise and completely closes the slot 187. Slot 183 remains wide open; by this means, less water is admitted in the automatic rich, as, in the automatic lean position, more water is needed as the engine is more prone to detonate with a lean mixture than with a rich mixture. When the valve 77 and 188 are moved clockwise, then both the slots 183 and 187 are completely covered. This is the position for idle cut-off.

The function of the pipe 173 is to insure that the pressure in chamber 178 is equal to the pressure in the chamber 53. Hence, the drop of pressure through the restrictions 185 and 181 is the same as the drop in pressure past the restrictions 47 and 48. The pressure upstream from the restrictions 181 and 185 is the pressure in the pipe 176 because the water tank 174 is freely opened to the passage 176 and the valve 162 is wide open. Hence it is that the flow of water increases as does the flow through the orifice 48 and the flow through the orifice 47. The only difference is that when the fuel orifice 48 alone is used, both the restrictions 181 and 185 are functioning,

and when the restricted orifices 47 and 48 are both in use, then the opening 181 is closed and the orifice 185 is inoperative. In other words, when both fuel orifices are used, only one water orifice is used; when both water orifices are in use, only one fuel orifice is in use.

Fig. 2 shows what actually happens under four different working conditions:

Rich—no water

1. A, B, C, D, E.—The valve 162 is closed and the controls 77, 86 and 186 are in their rich position, that is, about 30° anti-clockwise from the position shown in Fig. 1. From A to B there is an empirical relationship between fuel flow and airflow in the idle and off idle range. From B to C the fuel/air ratio is determined by the counter balanced diaphragms 54 and 37 and by the size of the variable orifices 47 and 48 which are opened in a fixed relationship with the air throttle 12. From C to D the power enrichment valve 100 opens against spring 101 by means of differential from venturi 57, reduced by restrictions 99 and 160. The maximum fuel/air ratio attained at D occurs when valve 100 is wide open at which time restriction 91, together with variable orifices 47 and 48, governs the fuel flow. Note the restriction 92 is now out of action as less enrichment is needed with the rich cruising mixture of 0.080 B-C.

Rich—with water

2. A, B, C, C¹, E.—The valve 162 is now open, the port 183 is open and 187 is partly covered as valve 188 is in its position to provide the lesser quantity of water required with the richer mixture. When the solenoid 163 is energized by switch 164 to open water admission valve 162, all fuel flow through valve 100 and restriction 91 is cut off by water pressure operated diaphragm valve 107. The fuel/air ratio shown on line BC¹ is due to variable fuel restriction 47 and 48. Unmetered fuel pressure in chamber 56 is impressed on water tank 174 and hence exists in unmetered water passage 165. Metered fuel pressure from chamber 53 is led by pipe 173 to chamber 172. Water regulating diaphragm 171 actuates water control valve 169 to adjust water flow across throttle operated water restriction 181 to give metered water pressure in chamber 178 equal to metered fuel pressure in chamber 172. Water restrictions 181 and 185 are of sufficient size to bring combined ratio of water and fuel to air ratio to line DE on Fig. 2. Switch 164 is energized only when the engine is operated at airflows in excess of 95% of maximum as below this point there is no need to use water.

Lean—no water

3. A, F, G, D, E.—The valve 162 is closed and the controls 77, 86 and 188 are in the position shown in Fig. 1. From A to F there is an empirical relationship between airflow and fuel/air ratio determined by throttle operated restriction 48 and parallel adjustable valve 52. From F to G the fuel/air ratio is determined by the two diaphragms 54 and 37 and by the throttle orifice 48 as throttle operated orifice 47 is closed by control 77. From G to D the power enrichment valve 100 opens against spring 101 by means of full differential pressure from venturi 57 as restriction 160 is closed by control 86. The maximum fuel/air ratio attained at D occurs when valve 100 is wide open at which time restrictions

91 and 92, together with variable orifice 48, govern the fuel/air ratio.

Lean—with water

4. *A, F, G, G¹, E.*—The valve 162 is open and the controls 71, 86 and 188 are in the position shown in Fig. 1. Ports 183 and 187 are both wide open as valve 188 is in the position to provide the greater quantity of water required with the leaner mixtures. When switch 164 is closed energizing solenoid 163 and opening water valve 162, pressure operated diaphragm valve 107 closes off all fuel from restrictions 91 and 92 in a previously described manner. The fuel/air ratio is now as shown on line GG¹ and is determined by the variable fuel restriction 48. However, both parallel throttle operated variable water restrictions 181 and 185 add metered water to the system in a manner previously described to bring the total water and fuel/air ratio up to the line DE on Fig. 2. Switch 164, as before, is energized only when the engine is operated at airflows in excess of 95% of maximum as below this point there is no need for water.

What I claim is:

1. An engine fuel supply system comprising an air intake, an air restriction therein, a source of fuel under pressure, a fuel supply passage connected thereto, a fuel restriction, means responsive to the drop in pressure therein, automatic means responsive to the depression in said air restriction acting to balance said means responsive to the drop in pressure at said fuel restriction, means responsive to the unbalance to vary the pressure downstream from said fuel restriction so as to maintain the desired fuel/air ratio, a source of anti-detonating fluid under the same pressure

as the source of fuel, a passage therefor, means for introducing the anti-detonating fluid into the air entering the engine comprising a restriction in said passage, automatic means for maintaining the pressure downstream from said fluid restriction equal to the pressure downstream from said fuel restriction, a first valve controlling the size of said fuel restriction, a second valve controlling the size of said anti-detonating fluid restriction mechanism interconnecting said valves for simultaneously opening said second valve and closing said first valve whereby when the first valve is moved in the direction to reduce the area of said fuel restriction then the second valve is moved so as to increase the area of said fluid restriction.

2. A device as set forth in claim 1 in which there are interconnected means for simultaneously varying the restriction in the air stream, the restriction in the fuel passage and the restriction in the passage for anti-detonating fluid.
